BELT-MAKING MACHINE.

1,123,459.

Specification of Letters Patent.

Patented Jan. 5, 1915.

Application filed December 13, 1913. Serial No. 806,595.

To all whom it may concern:

Be it known that I, ARTHUR D. WRIGHT, a citizen of the United States, and a resident of Toledo, in the county of Lucas and State of Ohio, have invented a certain new and useful Belt-Making Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to belt making machines, but is not restricted to such use as it may be used in any connection for which it may be adapted or appropriate.

The object of my invention is the provision of a machine of this character which is operable to make multiple-ply belting from a strip of belting material, such material being marked, cut and folded by the machine into belts of predetermined widths and thickness.

A further object of the invention is the provision, in a machine of this character, of means for feeding a plurality of strips of belting material, one over another, to a folding device where the edge portions of such strips are folded over together in meeting relation to double the number of plies of the belt in a simple and efficient manner.

A further object of the invention is the provision of means for stamping identification or other marks or data on one side of the belting after being folded as above described, and afterward folding or doubling the belting transversely upon itself to turn the stamped side thereof inward and to increase the plies of the belting. Further objects and advantages of the invention will be apparent from the following detailed description thereof.

The invention is fully described in the following specification and while, in its broader aspect, it is capable of embodiment in numerous forms, a preferred embodiment thereof is illustrated in the accompanying drawings, in which,—

Figure 1 is a side elevation of the left end portion of a machine embodying my invention. Fig. 2 is a similar view of the right end portion thereof. Figs. 3 and 4 are top plan and horizontal sectional views of the

left end portion of the machine. Figs. 5 and 6 are similar views, respectively, of the right end portion of the machine. Figs. 7 and 8 are cross-sections of the machine on the lines *x*—*x* and *y*—*y*, respectively, in Fig. 5. Fig. 9 is a detail of the pressure wheel of one of the belting folding parts. Fig. 10 is an enlarged detail of one of the stylographic instruments. Figs. 11 and 12 are details of a portion of the control mechanism of the machine. Figs. 13 and 14 are enlarged details of the strip winding bobbins or spools. Fig. 15 is a perspective of a portion of the doubling over means of the machine with a part thereof removed. Fig. 16 is an enlarged sectional detail of a portion of such means, and Figs. 17, 18 and 19 are cross-sectional diagrams of different forms of belting.

Referring to the drawings, 1 designates a machine frame, which is of elongated form and of a width suitable to accommodate belting material strips of maximum width. Located at one end of this frame, the right hand end, in the present instance, is a spool 2 adapted to carry a roll of belting material preparatory to the inward passing of the same through the machine. The belting strip *a* in unwinding from the roll 2 passes over an idler-roll 4 at the adjacent end of the frame, and thence lengthwise over the upper portion of the frame 1 and over an idler-roll 5 at the opposite end thereof, after which it winds upon a spool 6 at the left end of the frame, as shown in Figs. 1 and 2. The spools 2 and 6 have their shafts journaled in bracket arms 7 projecting from the respective end portion of the frame.

The frame 1 is provided on its top adjacent to the side edges thereof with guide-bars 8 adapted to receive and guide the respective edges of the material *a* and being adjustable transversely of the frame to vary the distance therebetween as the width of the material acted upon may require. The bars 8 extend lengthwise of the frame, being mounted on a top plate or table portion 9 thereof, and are adjustably secured thereto by bolts 10 projecting from the bars down through registering slots 11 in the top plate, as shown in Figs 3 and 7.

A set of standards 12 rise from the sides of the frame 1 without the guide-bars 8, and extending between a pair of these standards with its ends journaled for rocking move-

ments therein is a shaft 13, which is disposed above the top of the frame and carries one or more stylographic instruments 14. Each of these instruments, as best shown in Fig. 10, comprises a reservoir portion 14^a and a nozzle portion 14^b extending downward and forward therefrom and provided near its free end with a discharge orifice 14^c. The portion of the nozzle 14^b containing the discharge orifice is intended to rest freely on the top surface of the belting strip *a* as it passes over the top portion 9 of the frame, thus leaving a longitudinal line on the surface of the strip due to the action of the stylograph, as will be readily understood. The marking of lines made on the belting strip *a* by the instruments 14 is used principally to determine the lines along which the strip is to be slit, as hereinafter described. One or more of these instruments may be used and relatively adjusted as desired, and when any or all of the instruments are not to be used the inactive instruments have their nozzles tilted to inoperative position and secured in such tilted position by set-screws 15 engaging the shaft 13.

When the belting strip *a* has been wound upon the spool 6, such spool with the material thereon is transferred to the position indicated by the spool 6^a, the shaft thereof being mounted in bearing brackets 16 rising from the left end of the frame, as shown in Fig. 1. Disposed over the end portion 30 of the frame 1 adjacent to the spool 6^a are two sets of opposing feed-rolls 17, 17 and an interposed set of cutter-wheel carrying shafts 18, on which latter are mounted one or more sets of coacting cutter-wheels 19. 35 The lower one of each of feed-rolls 17 has its shaft ends journaled in bearing-blocks 20, while the upper roll of each set is yieldingly urged toward the lower roll by springs 21, which bear downward upon bearing-blocks 22 in which the shaft ends of the upper roll are mounted. The bearing-blocks 20 and 22 of each set are carried by standards 23 rising from the frame sides, and the shafts 18 are journaled at their ends 40 in standards 24 rising from the frame. Tables 25 are disposed between the cutter-disks 19 and the respective sides of the feed-rolls 17, 17 in the plane of bite of the rolls and the cutter-disks, and support the belt strip in its passage between the feed-roll sets and the cutter-disks. The belting strip *a* after passing through the first set of feed-rolls 17 and being slit into two or more lengths or filler-strips *b* by the cutter-knives 19, thence passes between the second set of rolls 17 and the strips *b* are wound upon registering spools 26 carried by a shaft 45 that is journaled in bearing standards 27.

Each of the shafts carrying the different spools 2, 6, 6^a and 26 is composed of a

plurality of separable parts to facilitate a removal and placing of spools thereon. One of these shafts is illustrated in detail in Fig. 14, and comprises bearing-bushings 28 at the opposite ends thereof for journaling 70 in the respective bearings, such bushings being flanged at their ends to embrace the marginal edges of the bearings to retain the bushings therein. Each of these bushings has an axial hole therethrough, which, in 75 the present instance, is square in cross-section, to receive the connecting bar 29 of the shaft, which is projected through one of the bushings and into the other to prevent relative turning of the bushings, and has 80 a handle part or head 30 at one end to facilitate a longitudinal movement of the same relative to the bushings. The spools which are intended to be mounted on the shafts and are of any desired length to suit the 85 width of the belting strips winding thereon or therefrom, are shown, in the present instance, as comprising a barrel or sleeve member 31 carrying flanges 32 at its outer ends, and also being provided at such ends without the flanges with hub extensions 33 having openings therethrough, which are complementary to the bars 29, thus causing the spool and its carrying shaft to have rotation in unison. 90

A line-shaft 34 is mounted in suitable bearings 35 at one side of the frame 1 lengthwise thereof and carries a plurality of axially shiftable bevel-gears for meshing with gears on the adjacent ends of counter-shafts 100 36, 37, 38, 39 and 40, which are journaled in suitable bearings transversely of the frame at the left end portion thereof. The gears 41, which drive the respective shafts 36, 38 and 40, are of the single type, while the 105 gears 42 for driving the shafts 37 and 39 are disposed in connected sets, whereby each set may be shifted to place one or the other gear thereof into driving connection with the associated shaft for imparting forward 110 or reversing rotation thereto as desired. A shift-lever 43 is connected with each gear 41 and each of the gear sets 42 to control the shifting movements thereof. The shaft 36 has sprocket-wheel and chain connection 115 with the shaft carrying spool 6, as shown at 44 in Fig. 1. The shafts 37 and 39 have similar sprocket-wheel and chain connection, respectively, with the shafts of the lower feed-rolls 17 of each set, as shown at 45. The 120 shafts 38 and 40 also have similar sprocket-wheel and chain connection, respectively, with the lower shaft 18 and the shaft carrying the spools 26, as shown at 46.

Bearing standards or frame parts 47 rise 125 from opposite sides of the frame 1 forward of the standards 27 and are provided with aligned sets of bearings in which spool carrying shafts 48 are journaled. The sets of bearings for the shaft 48 are shown, in the 130

present instance, as being four in number and arranged in any suitable manner to facilitate the simultaneous feeding of belting strips from spools mounted on all or a portion of such shafts as it may be desired to make belting containing one or more filler strips, as hereinafter more fully described. One of the shafts 48, the one mounted in the present instance in the set of bearings 49, is intended to carry a long spool 50 from which the wrapping strip *c* of a belt unwinds, while the other shafts 48 are intended to carry spools 26 with the filler strips *b* thereon.

15. Mounted on standards 51 in advance of the standards 47 is a set of feed-rolls 52, the upper of which serves as a yielding pressure roll, while the lower is the drive roll and has chain and sprocket-wheel connection 53 with a subjacent shaft 54 that is journaled in the frame 1 transversely thereon. This shaft has geared connection with the line-shaft 34, the gears of such shaft comprising a pair 55, which are axially shiftable into engagement with one of the other sides of the gear on the shaft 54, and have their movements controlled by a shift-lever 56.

The respective strips *b* and *c*, as they feed from a desired number of the spools 26 and the spool 50, pass together between the set of feed rolls 52 with the filler strips *b* disposed above and centrally of the strip *c*, transversely thereof, and thence into edge folding members 57 disposed in the line of travel of the opposite edge portions of the strips. The folding members 57 are mounted for relative transverse adjustment on a table 58, which is supported by the standards 12 at opposite sides of the frame 1. The members 57 are of substantially U-form in cross-section with their open sides facing each other and gradually converge or approach each other from their receiving to their outlet ends, the space between the outer edge portions of their inlet ends being substantially equal to the width of the wrapping strips *c*, while the space between the outlet ends thereof is substantially equal to the width of the filler strips *b*. The mouths or inlet ends of the members 57 are of greater vertical depth than the outlet end portions thereof and are suitably fashioned, as best shown at 57^a in Figs. 2 and 15, to cause a gradual rolling or folding of the edge portions of the strip *c* over the respective side portions of the filler strips *b* with the edges of the wrapping strip substantially meeting along the longitudinal center of the filler strips, as illustrated in Fig. 17.

Mounted on the table 58 over the forward or outlet end portions of the members 57 is a guide 59 for the overturned edges of the wrapping strip *c*, such guide being carried by inverted U-shaped standards 60,

which are fixed to the table 58 at the outer sides of the members 57. The guide means 59 is provided in longitudinal alignment with the longitudinal center of the belt strips *b*, *c* with a dependent web 61, from the lower edge of which project outwardly the opposing horizontally-disposed ledge portions 62, 62. As the opposed side portions of the strip *c* are folded over the respective edge portions of the strip or strips *b* the edges of the strip *c* are prevented from overlapping one another due to the projection of such edges over the respective ledges 62 and having contact with the web 61. The edge folding members 57-57 may be relatively adjusted transversely of the table to suit the width of the strips *c* being employed, such adjustment being effected by the projection of retaining bolts 63 for the members 57 through registering transversely extending slots 64 in the table 58.

Mounted in standards 65 in advance of the outlet end of the edge folding members 57, 57 is a set of feed-rolls 66, the lower of which has sprocket-wheel and chain connection 67 with a subjacent shaft 68, which has shiftable reversing gear connection, as at 69, with the line-shaft 34, a lever 70 controlling such connection. The upper roll 66 of the set is held in yielding coaction with the drive-roll 66 by means of springs 71, or in any other suitable manner. A printing cylinder 72 is carried for free rotation by arms 73 projecting rearwardly from a shaft 74, which is mounted at its ends in bearing standards 65. The cylinder 72 is intended to rest freely upon the belting between its point of emergence from the folding members 57 and the set of feed-rolls 66 and to stamp an identifying mark on the upturned side of the belting, such side being disposed within the belting when the same is complete, as hereinafter described.

When a wide belt, such for instance, as a thirty inch belt, is being made, two of the belting sections shown in Fig. 17, which sections may be designated A, are disposed one over the other with the folded over edge sides thereof inwardly disposed, as shown in Fig. 18, such sections being then sewed together to complete the belt. When such wide belt is being made by the machine the belting after emerging from the feed-rolls 66 passes over a conveyer apron 75, by which it is carried to the right or forward end of the machine into position to be taken off onto a long table (not shown), which is provided for supporting the same. The conveyer apron 75 is guided by rolls 76, which are journaled at their ends in registering portions of side frames or standards 78. The forward roll 76, in the present instance, has sprocket-wheel and chain connection 79 with a cross-shaft 80, which is journaled transversely of the frame 1 in suitable bear-

ings provided therein and has one end in geared connection, as at 81, with the main shaft 34. A shift-lever 82 is provided for one of the gears 81 to shift the same into 5 and out of engagement with its companion.

When a belt, which is half the width of one of the belting sections A, is to be formed, such section after emerging from the feed-rolls 66 enters a doubling trough 83, which 10 is mounted in advance of said feed rolls on a table top or frame part 84 that is carried over the apron 75 by the standards 78. The trough 83 has its rear or inlet end of a width substantially equal to that of the belt section A and the sides thereof converge to 15 gradually narrow and deepen the trough, the outlet end of such trough having its sides quite close together and of a depth substantially equal to the width of one-half of 20 a belt section A, as shown in Figs. 2 and 5. The belt section A is pressed at its center or along the longitudinal fold line thereof to the bottom of the trough 83 at or adjacent to its outlet end by a pressure wheel 85, 25 which is carried by a fork 86, the stem portion of which projects up through a super-posed bearing 87 in a frame part 88. A coiled compression spring 89 encircles the stem portion of the fork 86 and serves to 30 exert a yielding downward pressure on the pressure wheel. The frame 88 rises from the forward end portion of the frame part or standard 78 and forms bearings for a set of vertically disposed feed rolls 90, which 35 are disposed in advance of the outlet end of the trough 83 with their bite in register therewith. The upper ends of the shafts carrying the rolls 90 have geared connection, as at 91, with a shaft 92, that is mounted in 40 the upper portion of the frame part 88 transversely thereof and has one end in sprocket-wheel and chain connection, as at 93, Figs. 2 and 5, with a shaft 94, which is suitably mounted in the lower portion of the 45 frame 1 transversely thereof. The shaft 94 has geared connection, as at 95, Fig. 6, with a main shaft 34, and one of such gears is shiftable into and out of mesh with its companion and controlled by a lever 96. The 50 passing of a belt section A through the trough 83 doubles the same into the form shown in Fig. 19 and designated B. The sewing of the doubled over parts together forms a six-ply belt if a single filler strip b 55 is used, an eight-ply belt if two filler strips are used, and a ten-ply belt if three filler strips are used, as will be apparent.

Power for driving the shaft 34 is shown, in the present instance, Figs. 2 and 6, as 60 being derived from a motor 97, which is mounted within the frame 1 and has any suitable connection with said shaft as shown.

In the use of my improved belt making machine a strip a of any suitable material 65 for belts is fed from a roll or spool 2 length-

wise of the machine between the guide bars 8 thereof, being marked lengthwise thereof during such course of movement by one or more of the stylographic instruments 14, and winding at the opposite end of the machine on a roll or spool 6. The spool 6 is then mounted on the shaft which is journaled in the bearing arms 16 and the material a fed therefrom through spaced sets of feed-rolls 17, 17 and an interposed set of 70 slitting knives 19, and the separate strips b, which are formed by the slitting process, are then wound upon individual spools 26, which are removably carried by the shaft which is journaled in the bearing parts 27. 80 If a thirty inch belt section A is to be made the material strip a is sixty inches wide and is cut into two strips, each of thirty inches width, or if desired the strip a may be cut into narrower sections for the making of 85 narrow belts. If a belt section A is to be made with one filler strip b, only one of the spools 26 with a strip b thereon is mounted on a shaft in the frame part 26, the other filler spool 26 being laid aside for subsequent use. Whereas if the belt section A is to be provided with two or more filler strips b the desired number of filler spools 26 are mounted on the shafts 48 for such purpose. 90 A roll 50 containing a wrapping strip c of 95 twice the width of the section A to be formed is mounted on the proper shaft 48 provided therefor and the strip c from such spool or roll and the strip or strips b from the spools 26 feed together between the feed-rolls 52, 52 and into the edge folding members 57, 57 with the strip or strips b disposed over the wrapping strip c centrally thereof. As the strips b and c feed together into the edge folding members 57 100 and through the guide 59 the side edge portions of the strip c are turned over the strip or strips b with the edges thereof in substantial meeting relation and the whole is then pressed together in this folded form 105 by passing between the feed and pressure rolls 66, 66. If a belt similar to that shown in diagram in Fig. 18 is to be made the section A after leaving the feed-roll 66, 66 110 passes under the table 84 and is guided in its forward course of movement by the conveyor apron 75. When two of the sections A have been made the same are placed one over the other in inverted relation and 115 sewed together, as indicated in Fig. 18. The purpose of marking the inner side of the sections A by the printing cylinder 72 is to enable a manufacturer to identify his belt when returned for repairs or for other purposes. If a belt similar to that shown in Fig. 19 is to be made a section A, after passing between the feed-rolls 66, 66, enters the 120 folding trough 83 by which it is doubled upon itself and thence passes between the pressure and feed rolls 90, 90, after which 125 130

it is ready for sewing to secure it in such folded form.

I wish it understood that my invention is not limited to any specific construction or arrangement of the parts except in so far as such limitations are specified in the claims.

Having thus described my invention, what I claim as new, and desire to secure 10 by Letters Patent, is,—

1. In a belt making machine, edge folding means, and edge guiding means having a pendant web portion intermediate opposite side portions of said folding means, and 15 flanges projecting outwardly in opposite directions from such web portion.

2. In a belt making machine, a pair of opposed edge folding members having overhanging or roof portions, and edge guiding 20 means superimposing said portions and having an inverted T-shaped part depending therefrom with its arms projecting under said overhanging portions.

3. In a belt making machine, a belting-25 strip doubling trough, and yielding pressure means extending down into the trough for holding a strip therein in its passage therethrough.

4. In a belt making machine, edge folding means and doubling means for pro-

gressively acting on a belting-strip to edge fold and double the same as it is drawn therethrough, and means intermediate said folding and doubling means for applying an identification mark on the side of the 35 strip which is doubled in.

5. In a belt making machine, means for imparting lengthwise feeding movements to a belting strip, separate means for progressively acting on a strip in its feeding movement to edge fold and then double the same, and means intermediate the edge folding and doubling means for applying an identification mark to the side of the strip which is disposed inwardly and doubled. 40

6. In a belt making machine, separate means disposed one in advance of the other for imparting successive folds to a belt strip fed therethrough, and means intermediate said folding means for applying a mark to 50 a portion of the strip which is hidden from view when the strip is folded.

In testimony whereof, I have hereunto signed my name to this specification in the presence of two subscribing witnesses.

ARTHUR D. WRIGHT.
